COMBINATION RECEPTACLE

James J. Sokos, Richwood, W. Va., assignor of
one-half to Thomas G. Sokos, Richwood,
W. Va.

Application March 11, 1939, Serial No. 261,334

1 Claim. (Cl. 312—78)

This invention relates to improvements in kitchen and table articles and pertains particularly to an improved combination container for table use.

5 The present invention has for its primary object to provide a combination condiment and toothpick container which comprises a pair of condiment receptacles having means associated therewith whereby the contents of either may be readily obtained, associated with a novel type of toothpick container which is designed to normally maintain the picks in covered or protected condition but which is readily operable to display all 10 of the toothpicks so that the same may be removed as required.

Another object of the invention is to provide in 20 a device of the character described, a toothpick container and dispenser of novel form wherein the picks as a group may be drawn partly out from the container when the latter is uncovered, so that the toothpicks may be obtained conveniently.

A further object of the invention is to provide in 25 a combination shaker receptacle for condiments having two or more condiment compartments, a novel means for preventing the condiment of one compartment reaching the discharge openings when the contents of the other compartment is being removed.

30 The invention will be best understood from a consideration of the following detailed description taken in connection with the accompanying drawing forming part of this specification, with the understanding, however, that the invention 35 is not to be confined to any strict conformity with the showing of the drawing but may be changed or modified so long as such changes or modifications mark no material departure from the salient features of the invention as expressed in the appended claim.

In the drawing:

Fig. 1 is a vertical sectional view through the receptacle embodying the present invention.

Fig. 2 is a sectional view taken on the line 2—2 45 of Fig. 1.

Referring now more particularly to the drawing, the numeral 1 generally designates the body portion of the combination receptacle embodying the present invention, which body is here shown 50 as being in the form of a disk having the annular edge wall 2 and the flat side walls 3. This body may be supported upon any suitable base such as the one here illustrated and indicated generally by the numeral 4. In carrying out the 55 present invention, the body 1 is interiorly divided

by the two partition walls 5 which between them form the narrow central chamber 6 which is vertically disposed, and the two side chambers 7 which are provided for condiments.

The edge wall 2 of the body is provided at the top end of the central chamber 6 with the opening 8 and secured within this opening and extending downwardly into the chamber 6, is a sleeve 9 of tubular form, the upper end of which projects above the wall 2. This sleeve 9 is provided with the longitudinally extending diametrical slots 10 which open through the inner or lower end of the sleeve and extend to a point substantially above said lower end. Within the sleeve there is slidably disposed the elongated receptacle 11 which is of circular cross-section and adapted to fit snugly within the sleeve so that it may have longitudinal movement therein without material side play. The lower end of this receptacle is rounded, as indicated at 12, and across the lower end there is secured a bar 13, the ends of which extend beyond the receptacle to provide laterally projecting guide fingers, each of which slidably engages in a guide slot 10. Thus these fingers limit the upward movement of the receptacle and the design of the toothpick dispenser is such that when the receptacle 11 is drawn upwardly to a position where a portion of the upper end will project from the upper end of the sleeve 9, the finger ends of the bar 13 will engage the upper ends of the guide slots and thus stop the outward or upward movement of the receptacle. If desired, single or independent fingers may be joined to the receptacle 11 in place of the bar 13.

30 The sleeve 9 is provided with a cap 14 which is adapted to frictionally engage over its upper end and attached to the inner side of this cap at its center is a chain or cord 15, the other end of which is secured to the inner side of the bottom 12 of the receptacle. This strand 15, which may be in the form of a fine chain, a cord or other flexible connection, facilitates drawing the receptacle 11 upwardly and it holds the receptacle in raised position when the cap 14 is allowed to hang at the outer side of the body.

40 The edge wall 2 is provided at each side of the toothpick dispenser, with a condiment discharge opening 16 and secured to the wall 2 and encircling each opening 16 is a discharge collar 17 upon the outer end of which is an apertured dispenser or sifter cap 18.

45 Secured to the inner side of the wall 2 at each side of the toothpick dispenser and at a point closely adjacent the same, is a shield plate 19 which extends the full interior width of the cham- 50 55

ber 7 in which it is located and projects across the adjacent opening 16, being spaced at the end remote from the end which is attached to the wall 2, from the wall 2 to provide the narrow 5 throat 20 through which the condiment may pass into the area 21 lying between the plate and the discharge opening or mouth leading to the nozzle 17. Since these plates 19 are arranged in downwardly divergent relation, being connected with the wall 2 at points above the two discharge nozzles, it will be readily apparent that when the shaker device is turned into the proper position where the condiment may flow through the throat 20 and into the area 21 to be shaken from the 10 adjacent apertured cap 18, the opposite guard plate 19 will prevent the condiment in that chamber from reaching the adjacent discharge nozzle 17.

From the foregoing, it will be readily apparent 20 that there has been provided in the device herein described, a novel combination toothpick dispenser and condiment shaker in which the contents of either condiment chamber may be readily shaken out without danger of accidentally getting 25 any of the contents from the other chamber and in which novel means has been provided for stor-

ing toothpicks in such a manner that they will remain clean and sanitary at all times.

What is claimed is:

In a dispenser device of the character described, a supporting body including a base, a vertically arranged sleeve carried by the base and having an open upper end and longitudinal slots formed therein from the lower end to a point substantially above said lower end, an elongated substantially tubular receptacle disposed within the sleeve 10 for sliding movement longitudinally therein, the receptacle being open at its upper end, means carried by the bottom of the receptacle forming lateral elements slidably disposed in said longitudinal slots to afford limited upward movement of 15 said receptacle, a removable cover cap for the upper end of the sleeve formed to fit over the sleeve, and a chain attached at one end to the inner side of the central part of the cap and connected at its opposite end to the inner side of 20 the central part of the bottom of the receptacle, said chain facilitating lifting the receptacle and disposing the cap at one side of the sleeve for the maintenance of the receptacle in raised position.

JAMES J. SOKOS. 25
